UNITED STATES PATENT OFFICE.

LAFORREST A. SHATTUCK, OF BLOOMSBURG, PENNSYLVANIA.

FOUNTAIN-PEN.

SPECIFICATION forming part of Letters Patent No. 450,197, dated April 14, 1891.

Application filed September 19, 1890. Serial No. 365,468. (No model.)

To all whom it may concern:

Be it known that I, LAFORREST A. SHATTUCK, a citizen of the United States, and a resident of Bloomsburg, in the county of Columbia and 5 State of Pennsylvania, have invented certain new and useful Improvements in Fountain-Pens, of which the following is a specification.

My invention relates to fountain-pens; and it consists in the peculiar construction and combination of parts herein shown and described and specifically claimed.

Many unavailing efforts have heretofore been made to construct an under-feed pen which would work as perfectly as an upper feed, all resulting at best in an irregular flow of the ink and none giving as prompt response to the first stroke of the pen in writing as the upper feed. My present device overcomes in the most simple manner all difficulties of this 20 character, and I am now able to construct a pen which works as well when adjusted for a lower feed as for an upper feed and admitting of greater ease in the adjustment of its parts.

Referring to the drawings, which are made 25 part of this specification, Figures 1 and 1* are central horizontal longitudinal sections of pens, illustrating preferred modes of embodying my invention when employing a single feed with the long governor. Fig. 2 is a 30 cross-section through the line *v v* of Fig. 1. Fig. 3 is a cross-section through the line *w w* of Fig. 1. Fig. 4 is a cross-section in the line *x x* of Fig. 1. Fig. 5 is a top plan view of the combined pen-seat and feed device shown in Fig. 1, and Fig. 6 is a central longitudinal section of the same. Fig. 7 is a plan view of the pen. Figs. 8 to 27 show slight changes in the arrangement and construction of some of the parts.

40 A is the reservoir, which may be in the form of a cylindrical, hexagonal, or octagonal tube. It has at its upper end a plug B, adapted to fit air-tight by a screw-thread joint or otherwise. The rear end of this plug has the usual seat for an ordinarily-constructed cap when the pen is in use. Its forward end from the screw-thread forward is reduced in size and has its socket *b'* extending nearly to the rear end of the plug. This socket is to provide a means for the longitudinal adjustment 45 of the governor, hereinafter described, and may be of any desired length. This reduced

portion of the plug could be constructed separately and suitably attached to the plug, or it might be dispensed with, as the screw-thread portion could contain a socket sufficiently deep for the adjustment of the governor, provided the latter was made sufficiently long, as shown in Figs. 8 and 9, or a socket may be formed in the upper end of the 55 nozzle, as in Figs. 22, 24, and 25, which I prefer on the ground of economy.

As is plainly shown by Fig. 1, the plug B may be formed in two parts to provide a means for operating the governor at its rear 60 end. The part B' is double screw-threaded and adapted to register with the rear end of the reservoir and open end of the part B², which is removable for the purpose of adjusting the governor. The part B' may be 65 internally screw-threaded to receive a corresponding thread on the governor; but a frictional hold, as shown in Fig. 8, will answer very well. The reduced extension *b* of the socket *b'* extends above the ink-line, so that 70 no ink will be liable to escape through the socket; but should any ink so escape the part B² of the plug will retain it.

The open or forward end of the reservoir may be counterbored for a short distance, as 75 at *a*, to form, in connection with a radial groove or depression on the nozzle, a safety-chamber, as and for the purposes hereinafter described. This counterbore should extend in about three-sixteenths of an inch, terminating in a shoulder *a'*, (more clearly shown in Fig. 8,) beyond which the reservoir may be internally screw-threaded to receive the corresponding thread on the nozzle-section.

C is the nozzle or pen section of the case. 80 It is tubular, having the passage through it adapted to receive the pen and feeding device. This passage has a right-angled shoulder, as at 85 *c*, formed about one-sixteenth of an inch in from the front end of the passage. This shoulder, against which the right-angled shoulder on the pen abuts to prevent lateral movements of the pen, also forms a stop to prevent crowding the pen in too far. At a point forward of the frictional molding *c'* I form another shoulder, as shown at *c*², to re-enforce and strengthen the rear end of the nozzle; but this will only be necessary when employing 90 an ordinary pen having a broad heel with-

out shoulders, as the wall of the rear end of the nozzle must be formed thick enough to provide for the safety chamber groove c^3 , so as not to weaken the nozzle at that point. The 5 end of the nozzle which fits into the reservoir is made longer than usual and screw-threaded for a portion of its length only. This portion has a mouth flaring rearwardly to lead the ink quickly into the nozzle. Between the 10 screw-thread and the frictional molding c^4 I form upon its periphery a radial groove or depression c^3 , not less than one-eighth to three-sixteenths of an inch wide and cut to a suitable depth to form a chamber large enough 15 to catch what ink is forced along the screw-thread when adjusting the nozzle to the reservoir.

It is a great convenience to have a fountain-pen case formed in separable parts for 20 filling; but the oozing of ink out around the joint when adjusting the parts has proved a serious annoyance. I partially overcame this difficulty in a former application by extending the nozzle slightly beyond the screw- 25 thread in reduced diameter. I now form the screw-thread upon the extreme end and reduce its diameter forward of the point of attachment to the reservoir, whereby a recess or chamber G, which I term a "safety-chamber," is formed, which catches the ink and 30 furnishes the best safeguard against difficulties such as named. At the forward end of this chamber I may form a pivot or shoulder c^7 large enough to closely fit into the recessed 35 end of the reservoir to strengthen the nozzle at this point; but this will not be necessary if the walls of the nozzle are made sufficiently thick and strong. At the forward end of the cap-seat c^5 on the nozzle I form a milled depression c^6 to provide greater frictional hold 40 for the fingers in unscrewing the nozzle. Upon the periphery of the nozzle at its front end I form an abrupt re-enforcement, ridge, or molding c^8 for a finger-stop, as more fully set 45 forth in a previous application. The nozzle may be internally screw-threaded, as in Fig. 24, at its upper end to form a socket for the governor.

D is the ink-suspension rod and governor. 50 Its rear portion may be adapted to be held by a screw-thread or by friction or otherwise in a suitable socket or passage, as b' , for instance, provided for its longitudinal adjustment either in the plug B or upper end of 55 the nozzle. Fig. 8 shows a bulbed end to aid in its support. It is formed by splitting the end and conforming the two lips thus formed, by heat or otherwise, into shape like a bulb, as at b. Its forward end is preferably tapering 60 or conical and adapted to fit in a preferably conical-shaped passage c' in the nozzle, and is suspended intermediate of the walls of said passage, forming a conical-shaped annular suspension-passage or ink-weir, wherein ink 65 is allowed to accumulate, and by reason of the attraction of adhesion existing between the ink and the walls of an annular passage

of this character the main body of the ink is sustained and the ingress of air controlled, as more fully set forth in a previous application. When the passage c' is made conical, the free end of the governor need not be tapered; but I prefer to so construct it. 70

E is the combined pen-seat and feeding device. (Clearly shown in the drawings.) Its preferable form for an under and double feed (see Figs. 1, 5, 6, and 24) has a base or body e, adapted to fit the bore of the nozzle, said body portion having a horizontal passage c' extending from end to end through it, preferably conical, or having a series of steps formed by making said passage with a number of different-sized drills, as shown in Fig. 1* the object being to make the pen sensitive to the least movement of the governor longitudinally in gaging the flow of ink by regulating the ink-supply. 85

From one side of the body a tapering lip e^2 extends forward to nearly the point of the pen. From near the point of this lip on its pen-surface a peripheral longitudinal groove or slot e' extends to the rear end of the body portion. This is to form with the pen an enclosed ink-channel direct to the nibs. The body portion may be bisected by a slit to 90 form two arms, as e^8 , to facilitate the passage of ink; or instead of a slit one or more cross or deflecting passages may be cut, as at e^7 , for the escape of ink from the channel e' to the ink-weir and to furnish a circulation 95 in the nozzle, so that all ink will run back into the reservoir when not in use. 100

Fountain-pens which do not have a direct ink-channel to the pen, but depend upon capillary attraction to draw the ink down, are 105 liable to clog, as sufficient ink will be retained between the pen and feed-bar to dry up and form a gum difficult to remove. On this account a gravity-pen, if constructed as herein described, is found most reliable. The rear end of the body portion of the feed device 110 may have a slit along the bottom of the channel e' , penetrating to the passage c' , as an equivalent to the cross-passage e^7 , or the channel e' and passage c' may be independent of 115 each other throughout. Instead of a groove the feed-channel might be formed by a chamfer and the body of the pen-seat might have a reduced portion, forming a shoulder, said shoulder abutting against the shoulder c^2 , as 120 shown in Fig. 8. I sometimes form the ink-passage c' by a tapering horizontal slit or slot bisecting the feeder in line with the groove e' the entire length of its body portion. The front end of the body portion is 125 provided with a suitable pen-seat to receive and hold the shank of the pen. The pen F may be curved or flat, and is preferably formed with shoulders ff to abut against the shoulder c in the nozzle and thus prevent lateral movements of the pen. 130

The construction of my fountain-pen is simple, being free from all complications and effectually overcomes all objections to under-

feed pens, as its response to the first stroke of the pen when adjusted for an under feed is as prompt as with the upper feed, and will not blot or skip, and has the upper surface of the pen unblemished by ink and feed-bars, which to some are objectionable. It has the further merit of cheapness of construction and ready adjustment of its parts. It will also be readily understood by reference to the drawings that the governor not only regulates the flow of ink, but also keeps the nozzle clean.

Fig. 10 shows the feeding device with one passage through it. The pen-slot bisects this passage at its front end, leaving a portion of the passage above the pen for the ink-weir, which has its open end above the pen.

In Fig. 11 I show the feed-channel formed within or through the body portion and the ink-weir passage formed by a groove on the periphery. The pen is seated in a transverse slot and the governor formed like a flat watch-key with tapering point adapted to the shape of the groove. Its central portion impinges against the walls of the nozzle and its rear end projects beyond the rear end of the nozzle, by which means it is operated longitudinally.

Fig. 1* shows slight changes in the feed device E to adapt it to an upper feed. The pen is seated in a transverse slot cut across the center of its body portion. The feed-channel e' is cut along the under side of the lip e^2 to form an ink-channel over the pen. The mouth of the passage c' is made flaring outwardly, but from a contracted throat opposite the heel of the pen said passage is flaring rearwardly by a series of steps. The rear end of the body of this feeder is bisected by a slit extending forward to intercept the feed-channel groove e' , as shown in my patent previously cited. The governor is adjusted in a socket formed in the rear end of the reservoir and held by friction.

Having described my pen as constructed with a separable governor, I now proceed to show how a governor may be formed integral with the pen-seat and feed device, so as to secure an annular ink-weir beneath the pen, as shown in Figs. 12 to 21. I take a piece of rubber tubing in cylindrical form large enough to fit the bore of the nozzle, having a small perforation through it. I bisect this at its forward end transversely for about half its length through the center of its perforation. I then cut off part of the under half, leaving a short lip for the governor D. The upper lip e^2 is cut down thin enough to form a flexible feeder, leaving a shoulder d' . (See Fig. 15.) I then cut ink-grooves on the side and on the bottom the full length of the body. The under lip or governor D is tapered on all sides toward its point, so that when the pen is adjusted in the slit its edges will impinge against the side walls of the nozzle, holding the body of the feeder against the upper side of the nozzle, but leaving an an-

nular passage around the lip D beneath the pen. The rear end view of this combined feed device and governor is shown in Fig. 13 70 and a side elevation in Fig. 15, while Fig. 14 is a cross-section in the line $z z$ of Fig. 15.

Fig. 16 is a rear end view of a modification to the extent that only one groove is formed, which may be on the bottom or side, giving 75 two passages instead of four.

Fig. 17 shows the rear end of the feeder chamfered off on two sides to form ink-passages instead of grooves and bisected by a horizontal slit extending forward to near the 80 end of the governor-point D, forming two parallel bars, broadly claimed in my patent No. 402,864.

Fig. 18 is a side elevation of a combined feeder, pen-seat, and governor having a 85 square or prismatic body, more clearly shown by end view, as in Fig. 19. This square body fitting in the circular passage of the nozzle forms four ink-passages around the feeder. Fig. 20 shows this form with a central perforation, and Fig. 21 has two horizontal slits 90 at its rear end.

In all the forms represented in Figs. 12 to 21 a plurality of ink-passages at the rear end of the feeder creates a circulation, and the ink 95 will always be brought down and suspended in the ink-weir c' around the governor-point D and will be deflected into the inclosed ink-channel over the pen and insure a steady 100 flow. On account of the cheapness of construction and ready adjustment for a lower or upper feed, I sometimes employ these forms when using a steel pen. I prefer to employ 105 a separable governor having a tapering point entirely disconnected from the feed device, as I can thereby better regulate the flow of ink.

Fig. 22 shows the pen attached to the side walls of the front end of the nozzle, a channeled semi-cylindrical feeder E, abutting 110 against the shoulder c^2 , and a tapered oval-shaped governor D, forming beneath the pen the conical-shaped ink-weir c' .

Fig. 23 shows a feeder passed through the pen, as claimed in a former application, and 115 a governor D, having an angular body impinging against the rear of the nozzle, and having two tapered points or prongs forming an annular ink-weir on both sides of the pen, above and below. Spaces are left open on 120 either side of the body of this governor for the passage of ink. I may extend the lower prong as far forward as the slit in the pen and bend it up, so as to form an ink-retainer. (Shown in a former application.) 125

Fig. 24 shows a screw-threaded socket in the upper end of the nozzle. The governor has a cylindrical body, screw-threaded, as at d^2 , and peripheral grooves for ink-passages, claimed in a former application, and a combined feed and pen-supporting bar H, having 130 its rear end seated beneath the pen and its forward portion passed through a perforated writing-pen and resting upon or in

close proximity to the nibs to give support to a flexible pen. Having broadly claimed this manner of adjusting a top-feed in a former application, I wish now simply to show 5 how it may be employed in combination with my feed device E and governor D. The under feed is constructed the same, except that it is cut away beneath the heel of the pen to provide a seat for the rear end of the bar H.

10 Fig. 24* is a cross-section through the line $x x$ of Fig. 24.

Fig. 25 shows a simple but excellent way of 15 adjusting the governor by means of a tubular-socket secured in the rear end of the nozzle. It is the same in principle as the tubular button shown in a former application, except that it is cut away on two sides to form ink-passages and has a reduced portion extending 20 forward to the heel of the pen and a reduced portion extending beyond the rear end of the nozzle for adjusting purposes. A short cylindrical or prismatic governor is adjusted in this socket, and its slightest longitudinal 25 adjustment will change the feeding power of the pen.

Fig. 25* is a cross-section through the line $z z$, Fig. 25.

Fig. 26 shows a semi-cylindrical grooved 30 feeder adjusted over the pen. The pen is secured to the side walls of the nozzle. The governor has a tubular body from the forward end of which a tapering lip extends beneath the pen.

Fig. 27 shows the nozzle and reservoir sections 35 constructed in one piece, which has the merit of cheapness. The pen and feeder can be easily removed for filling.

It is evident that slight changes in the manner of constructing and adjusting the governor 40 might be resorted to without departing from the spirit of this portion of my invention, which comprehends a rod longitudinally adjustable by a screw-thread or otherwise, having its extreme front end tapering or cone 45 shaped or adapted to form with a suitably-shaped socket-passage a tapering or cone-shaped annular passage or ink-weir open to the air at its forward end at the mouth of the nozzle by which ink is sustained and in- 50 gress of air controlled and the flow of ink regulated by said longitudinal adjustment. It has been found in practice that the nearer to the front of the nozzle the ink is brought down and sustained in an annular ink-weir 55 open to the air beneath the pen the more regular and certain will be the flow of ink and less liable to blot. In constructing the safety-chamber care should be taken not to form it so narrow as to be ineffectual and not 60 so deep as to weaken the nozzle at this point.

I have illustrated in Figs. 1, 8, 10, 22, 24, 25, 26, and 27 probably the simpler method 65 of construction when operating the governor longitudinally by means of the screw-thread adjustment or otherwise. It is evident that

the tubular extension b in Fig. 1 might be formed separable with its upper end screw-threaded and fitting a screw-threaded socket b' in the plug B and this extension operated at either end. In this case the governor B 70 could be made short and held by friction at its upper end in the forward end of the socket b' , or the extension b could have its forward open end screw-threaded to fit the corresponding thread on the governor. The governor 75 might be secured to a longitudinally-adjustable screw-threaded ring, said ring fitting the reservoir near its forward end, as shown in my patent No. 423,822. Other ways might be suggested for operating the governor inward and outward, and therefore I 80 do not wish to be limited to the special manner shown.

A pen constructed with an adaptable feed adjustment in the manner described is readily 85 adjustable to any hand or grade of ink and will always be clean and free from all objectionable features.

It will be readily understood by reference to the drawings that the governor acts as a 90 self-cleaner when adjusting the nozzle to the reservoir. It will also be seen that should one desire to write a coarse hand requiring an excessive amount of ink the governor may be removed temporarily, when the pen will 95 feed rapidly, though less amenable to control.

My governor when extending through the reservoir should not be confounded with those known constructions having fixed rods permanently attached to the upper end of the 100 reservoir, with their front ends terminating at the heel of the pen and serving as feeders, or used for the support of adjustable needles in stylographic pens.

An important feature in my invention relates to the construction and longitudinal adjustment of a governing suspension-rod having a free point suspended intermediate of the wall of a cone-shaped passage forming forward of the heel of an ordinary split-nib 110 pen a tapering annular ink-weir, by which the feed is graduated to meet the requirements of the writer; but I do not confine myself to a construction comprising said governor. 115

What I claim is—

1. In a fountain-pen, a safety-chamber, as G, formed between the periphery of the rear end of the nozzle and front end of the reservoir, substantially as and for the purposes described. 120

2. A fountain-pen nozzle having a radial groove or depression, as c^3 , between its screw-thread portion and friction-molding c^4 , whereby a safety-chamber, as G, is formed between 125 said depressed portion and front end of the reservoir, substantially as described.

3. A fountain-pen reservoir recessed at its forward end, as at a , to form a safety-chamber, as G, substantially as described. 130

4. In a fountain-pen having a safety-chamber, as G, the pivot or shoulder c' , substantially as and for the purposes described.
5. In a fountain-pen, a nozzle having a milled depression, as c^6 , substantially as described.
6. A fountain-pen comprising in its construction a split-nib writing-pen, a feed-bar bearing upon the nibs of the pen, a governor, as D, independent of the feed-bar, having a free point adapted to regulate by longitudinal adjustment the admission of air and the flow of ink, and a plug, as B, having socket-passage b' for the support and adjustment of said governor, substantially as described.
7. A fountain-pen comprising in its combination a split-nib pen, a feed-bar bearing upon the nibs of the pen, a governor, as D, independent of the feed-bar, having a suitable socket provided for its support and adjustment with its forward free end in tapering form, and its rear end projecting a suitable distance into the reservoir, and a nozzle having a cone-shaped passage adapted to receive the free end of the governor, forming a tapering annular ink-weir for the suspension of ink and regulation of the feed, substantially as described.
8. In a fountain-pen, a combined feeder, pen-seat, and governor adapted to form with a suitable passage, as c' , an annular ink-weir independent of the main feed-channel, substantially as described.
9. A fountain-pen having an adjustable governor, as D, and a passage, as c' , adapted together to form a conical-shaped annular ink-weir independent of the main feed-channel forward of the heel of the pen, a feed-channel, as e' , and one or more cross-passages, as at e^7 , substantially as described.
10. A fountain-pen having a reservoir provided with a plug B, a nozzle having a safety-chamber, as G, a feed device having passages $c'e'$, and a governor having a free point adapted to form with the passage c' a conical-shaped ink-weir, wherein the flow of ink is regulated by longitudinal adjustment, substantially as described.
11. A fountain-pen comprising in its construction a nozzle counterbored to form a square shoulder, as at c , and a pen having shoulders $f f$ abutting against said nozzle-shoulder, whereby undue lateral movements of the pen are prevented, substantially as described.
12. A fountain-pen comprising in its construction a safety-chamber, as G, and a nozzle shouldered or re-enforced, as at c^2 , substantially as and for the purposes described.
13. A fountain-pen having a safety-chamber, as G, and a nozzle-passage flaring rearwardly at its reservoir end, substantially as described.
14. In a fountain-pen, a feed device, as E, having a cylindrical body e , perforated by a cone-shaped passage, as c' , extending its full length, with a horizontal opening at its front end, a tapering lip e^2 , provided with an ink-channel formed by a groove or slot, as e' , cut in its periphery and extending from near its point to the rear end of the body portion and having a suitable pen-seat formed on or in the body of said feeder, substantially as described.
15. In a fountain-pen comprising in its construction a split-nib pen and a feed-bar bearing upon the nibs of the pen, a longitudinally-adjustable governing-rod independent of the feed device, having a screw-thread hold or adjustment and with its free point forming within the nozzle an annular passage, substantially as described.
16. In a fountain-pen, in combination, a reservoir, a nozzle, a pen, a governor, as D, and a combined pen-seat and feed device E, provided with a cylindrical body e , having passage c' , horizontally open at both ends for the passage of said governor, and having a tapering lip e^2 , provided upon its periphery with channel e' , extending to the main channel of the nozzle, substantially as described.
17. In a fountain-pen, a feed device, as E, having body e , with open passage c' extending from end to end and bisected to form two lateral arms, as e^8 , and having a tapering lip e^2 , provided with a suitable ink-channel, as e' , cut in its outer periphery and extending along the upper surface of said lip from near its point to the main passage of the nozzle, substantially as described.
18. A fountain-pen provided with a split-nib writing-pen, an open cone-shaped passage, as c' , and a device, as the governor D, having a free point adapted to be passed through said open passage, whereby the nozzle is cleaned by the longitudinal movement of said governor, substantially as described.
19. In a fountain-pen, the combination of a reservoir, a nozzle, a pen, pen-seat E, and feed-bar H with the governor D, all constructed and arranged to operate substantially as herein shown and described.

In testimony that I claim the foregoing as my invention I have signed my name, in presence of two witnesses, this 11th day of September, 1890.
